UNITED STATES PATENT OFFICE.

WALTER MINER, OF CRESTON, IOWA.

RAILWAY-CAR BRAKING AND SHIFTING APPARATUS.

No. 836,269.

Specification of Letters Patent.

Patented Nov. 20, 1906.

Application filed March 29, 1906. Serial No. 308,776.

To all whom it may concern:

Be it known that I, WALTER MINER, a citizen of the United States, residing at Creston, in the county of Union and State of Iowa, have invented a new and useful Railway-Car Braking and Shifting Apparatus, of which the following is a specification.

This invention relates to apparatus for switching railway-cars for the purpose of making up trains or delivering cars to any desired track in a railway yard, depot, or the like.

A further object of the invention is to provide a means whereby the cars may be given the required momentum to travel to near-by or to distant points without danger of injury to the cars and without the necessity of relying on the usual hand-brakes for checking the travel of the cars.

20 A still further object of the invention is to provide an apparatus in the form of an inclined plane over which the cars are moved by an engine or other mechanism and down which the cars may travel by gravity to tracks or sidings which communicate with the foot of the incline, all of the switches being under the control of a single operator, who may direct any car to any desired point, the operator being further enabled to govern 25 the speed acquired by the car during its descent, so that the momentum may be sufficient to carry the car the desired distance, but not sufficiently great to result in damage when the car is stopped by engagement with 30 another car or train at its destination.

A still further object of the invention is to provide an inclined plane having railway-track and provided with means whereby the wheels of a car or cars may be gripped for the 40 purpose of holding the car at any desired point, so that the operator may allow a car to descend and acquire speed throughout the whole or any part of the length of the inclined plane in accordance with the distance 45 which the car is to travel after leaving the plane.

A still further object of the invention is to provide an improved wheel-gripping means so arranged that a number of cars may be independently locked and released at different 50 points on the plane.

A still further object of the invention is to provide a wheel-gripping means of such construction as to automatically compensate for 55 variations in the width of the wheels or the distance between such wheels and which will

positively grip and hold the wheels without danger of injury.

A still further object of the invention is to provide wheel-gripping members of such construction as will permit of ready repair and replacing of worn or broken parts without the necessity of employing entirely new gripping devices throughout.

With these and other objects in view, as will more fully hereinafter appear, the invention consists in certain novel features of construction and arrangement of parts herein-after fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a perspective view of an inclined plane provided with car holding and locking devices arranged and constructed in accordance with the invention. Fig. 2 is a plan view of a portion of the same. Fig. 3 is a transverse sectional view of the device on the line 3 3 of Fig. 2. Fig. 4 is a detail perspective view of a portion of one of the wheel-engaging rails.

Similar numerals of reference are employed to indicate corresponding parts throughout the several figures of the drawings.

In the drawings is shown an inclined plane 10, having suitable traffic-rails 11, and the cars to be switched are pushed to the head of the plane by a switching-engine or the like and released one by one and allowed to travel down the plane by gravity, after which they may be directed to different tracks 12, leading from the foot of the plane. The tracks 12 lead to different points in the yard or depot, and the cars in descending the plane will acquire sufficient momentum to travel to any one of the yard-tracks, so that trains may be made up expeditiously and without the constant switching to and fro by yard-engines, as now practiced.

All of the mechanism is preferably arranged under the control of a single operator 105 stationed in a tower 15, connection being made between all of the switches and the tower and suitable mechanism being employed on the inclined plane for gripping and holding the cars and determining the distance of unimpeded descent of such cars, so that each car may acquire the necessary mo-

mentum to carry it to the desired point, and in this manner several trains for different divisions may be made up expeditiously or cars shifted to different tracks or sidings to be loaded or unloaded.

On each side of each of the traffic-rails 11 of the inclined plane are gripping-bars, these being disposed in pairs, the bars 16 and 17 being adjacent to one track and the bars 18 and 19 adjacent to the opposite track. Each of the gripping-bars is preferably angular in cross-section and its vertical gripping-face is provided with recesses for the reception of gripping or locking blocks 20, that preferably 15 are formed of a relatively soft metal in sections about two feet in length, so that any section may be readily replaced when worn or broken. The gripping-bars extend continuously for any desired distance under the 20 inclined plane and are designed to engage the opposite sides of the car-wheels and to hold the cars from movement, the mechanism being so constructed and arranged that a car may be gripped and held at any point in 25 the length of the plane, the distance through which it is free to travel being controlled by the momentum which must be acquired to travel the car to the desired point in the yard, the cars for the most distant points being allowed to travel the full length of the inclined 30 plane, while those for near-by points will be stopped near the foot of the plane and allowed to travel but a short distance, so that the velocity will not be sufficient to result in 35 damage when the cars strike against other cars already in position in the trains.

In order to operate the gripping-rails, a number of fluid-pressure cylinders are employed, there being four sets of such cylinders 22 23 24 25 in the present instance, and the cylinders of each set are connected by a pipe 26, which leads up to the signaling or other tower 15, suitable valves being employed under the control of an attendant for 40 the purpose of operating the pairs of cylinders independently of each other or simultaneously. Each cylinder of each pair carries a piston 30, that is connected by a rod 31 to a lever 32, and the latter is connected by 45 rods 33 and 34 to the two gripping-rails which constitute each set, so that when fluid under pressure is allowed to flow into the cylinder and the lever is moved each of the rod connections will form a fulcrum for the 50 transmission of movement to the other, and the gripping-rails which constitute each pair or set will be brought gradually together and will grip with equal force on opposite sides of the car-wheels, thus automatically compensating for wear or breakage of the wheels, 55 difference in the thickness of the wheels, and difference in the distance between the wheels of each axle.

The connections between the several sets 60 of cylinders and the gripping-rails are dis-

posed at different points in the length of such rails, and as the rails are more or less yieldable any one pair of operating mechanism may be moved to gripping position in order to stop and lock a car at any point, so that 70 when released the car may be allowed to travel any desired distance down the inclined plane to gather momentum which will carry it to its destination.

In place of using compressed-air cylinders 75 for operating the gripping-rails solenoids or direct mechanical connections may be employed, and these may be disposed at any desired distance from each other without departing from the invention. 80

I claim—

1. In apparatus of the class described, the combination with inclined traffic-rails, of a pair of wheel-gripping rails, and an operating means connected to the gripping-rails 85 and arranged to automatically compensate for variations in the wheels.

2. In apparatus of the class described, inclined traffic-rails, a pair of wheel-gripping rails, for each traffic-rail, and an independent 90 operating mechanism for each pair of gripping-rails.

3. In apparatus of the class described, the combination with inclined traffic-rails, of a pair of wheel-gripping rails for each traffic- 95 rail, independent operating mechanisms for each pair of gripping-rails, and means for simultaneously moving said operating means.

4. In apparatus of the class described, inclined traffic-rails, a pair of wheel-gripping 100 rails for each traffic-rail, an independent operating mechanism for each pair of gripping-rails, and means connecting the rails of each pair to automatically compensate for variations in the wheels. 105

5. In apparatus of the class described, the combination with inclined traffic-rails, of a pair of wheel-gripping rails, an operating-lever having fulcrum connections with the gripping-rails of each pair, each fulcrum 110 forming a center of movement for the other to automatically compensate for variations in the wheels.

6. A wheel-gripping device comprising a pair of rails arranged to simultaneously engage against opposite sides of the wheel, and means for pressing said rails with equal force against the sides of the wheels. 115

7. A gripping or holding device for car-wheels, comprising a pair of wheel-gripping 120 rails, and an operating means connected to both rails and arranged to exercise equal force on each of them.

8. A car-wheel gripping or holding device comprising a pair of members arranged to engage against opposite sides of the wheel, an operating-lever, and means connecting the lever to both members, whereby each acts as a fulcrum for the movement of the other. 125 130

9. In apparatus of the class described, inclined traffic-rails, a pair of wheel-gripping rails between which one of the traffic-rails is arranged, and a plurality of independently operable rail-actuating devices connected to said gripping-rails.
10. In apparatus of the class described, the combination with traffic-rails, of a pair of car-wheel-gripping rails between which one of the traffic-rails is arranged, a plurality of operating devices connected to the gripping-rails at different points, respectively, in the lengths of the rails, said operating devices being independently operable.
11. In apparatus of the class described, the combination with traffic-rails, of a pair of car-wheel-gripping rails, a plurality of operating members connected to the gripping-rails at different points, respectively, in the length of the latter, said operating devices being individually and simultaneously operable.
12. In apparatus of the class described, the combination with traffic-rails, of elongated wheel-gripping rails, sectional gripping-blocks on the inner faces of the rails, and dovetailed ribbed and grooved connections between the blocks and rails.
13. In apparatus of the class described, the combination with inclined traffic-rails, of a pair of wheel-gripping rails, a plurality of fluid-pressure cylinders arranged at different points in the length of the gripping-rails, and each having independent connections with said gripping-rails, and valved fluid-pressure pipes connecting the cylinders in pairs transversely of such rails.
14. In apparatus of the class described, an inclined plane having traffic-rails, a plurality of sets of rails leading from the foot of the inclined plane and having switch connections with the traffic-rails thereon, gripping-rails arranged on opposite sides of the traffic-rails, operating means for the gripping-rails, and switch operating and gripping-rail controlling mechanisms arranged at the central point for control by an operator.
15. In apparatus of the class described, an inclined plane having traffic-rails, a plurality of sets of rails leading from the foot of the inclined plane and having switch connections with the traffic-rails thereon, gripping-rails arranged on opposite sides of said traffic-rails, operating means for such gripping-rails, a switch-tower, connections leading therefrom to the switches at the foot of the incline, and means located in the tower for controlling the gripping-rail-operating devices.
- In testimony that I claim the foregoing as my own I have hereto affixed my signature in the presence of two witnesses.

WALTER MINER.
